UNITED STATES PATENT OFFICE.

HUGO NEWMAN, OF NEW YORK, N. Y.

STEREOSCOPIC APPARATUS.

1,018,439.

Specification of Letters Patent. Patented Feb. 27, 1912.

Application filed May 3, 1911. Serial No. 624,865.

To all whom it may concern:

Be it known that I, HUGO NEWMAN, a citizen of the United States, residing at New York, in the county of New York and State 5 of New York, have invented certain new and useful Improvements in Stereoscopic Apparatus, of which the following is a specification.

This invention relates to stereoscopic apparatus, the object thereof being to provide an improved apparatus of this character comprising an ornamental cabinet which will readily carry a large number of cards and in which a large number, as for instance a 15 hundred, of cards may be readily and quickly placed in position for use with the stereoscope and each of which cards may be easily and accurately manipulated into position to be viewed and also successively manipulated away from the viewing position without the necessity of handling the cards as is the usual practice, and in which also a description of the various views may be read while the stereoscope is in use in a very practical manner, and in which all of the several elements making up the apparatus, including the stereoscope and the cards, may be readily and quickly stored away.

In the drawings accompanying and forming part of this specification, Figure 1 is a cross-sectional view of the apparatus taken from front to rear, with the same in position for use; Fig. 2 is a similar view illustrating the cabinet closed; and Fig. 3 is a 35 front view of the apparatus with parts thereof broken away.

Similar characters of reference indicate corresponding parts in the different figures of the drawings.

40 This improved stereoscopic apparatus comprises a suitable casing or cabinet consisting of a bottom 2, a rear wall 3, and end walls 4 and 5, and having at the front thereof a pair of hinged or pivotally supported doors 45 6 and 7, one above the other. Each of these doors may be provided with glass if preferred. The lower door has its bottom molding so formed as to receive a book or other article and is provided with spring clips 8 50 for holding the same in proper position to be read. A suitable brace or support 9 is provided pivotally carried on the inside of one of the end walls and which may be shifted into position to support the lower 55 door at the proper angle when the same is

to be used as a reading desk, a suitable stop 10 being provided for holding the brace in its proper position.

The top of the structure comprises a fixed portion 11 and a swinging or shiftable portion 12, which shiftable top is carried by a pair of arms or brackets 13 pivotally secured to the rear wall of the cabinet, and a suitable set screw may be provided for imparting the desired friction to the arms so that the top will be held in the desired angular position in the manner hereinafter referred to. Connected with one of these arms by a suitable rod or link 14 is a card receiving member or board 15, which is pivotally secured at its ends to the side walls of the cabinet, this member normally constituting a partition dividing the cabinet into an upper and a lower compartment 17 and 18, but when the top is shifted into an inclined position to form a chute for the cards this partition is likewise shifted into position to constitute a chute for the reception of such cards, such partition being linked at its rear end to a swinging board or member 19 forming a part of the cabinet, so that when the dividing partition is shifted into its proper angular position to receive the cards as they are moved away from the stereoscope the rear of the cabinet will be opened so that the 85 cards may slide from the cabinet out at the rear side thereof and into a suitable receptacle which may be provided to receive them, while when the dividing partition is in its normal horizontal position the rear side of 90 the cabinet will be closed.

The upper door 6 is provided with a suitable molding 20 formed to furnish a stop so that it will remain in a substantially perpendicular position when opened to permit 95 the proper placing of the stereoscope and upper chute. This stereoscope 21 is carried by a longitudinally shiftable and swinging bracket 22, shown of U-shaped formation and comprising a pair of elongated slotted arms 100 23 and a cross bar or member 24, to which latter the handle 25 of the stereoscope is secured. The slotted arms 23 are each carried by a suitable set screw 26 carried by the side walls of the upper compartment of 105 the cabinet, and the arms when in a horizontal position are supported by staggered stops 27 carried by the side walls of the cabinet, so that the bracket will be held in proper horizontal position. On these set 110

screws the bracket may be swung into vertical position within the upper compartment of the cabinet in the manner shown in Fig. 2 when the stereoscope has been removed therefrom.

5 From the foregoing it will be observed that the stereoscope may be adjusted toward and from the cards by sliding the bracket thereby to obtain the proper focus.

10 The stereoscope may be of the ordinary construction, having the usual depending handle 25, which, however, in the present instance is provided with a suitable fastening means or set screw 28 for securing it to the cross bar 24 of the bracket just referred to. The stereoscope is also provided with a shiftable or swinging nose piece 29 which can be readily manipulated by the user so that it can be swung downward and thus permit the user to read whatever description may be upon the reading desk, after which a spring 30 connected with the nose piece will automatically return it to its normal position.

25 Carried by the adjustable top which forms, as hereinbefore stated, the chute for the reception of the cards to be used, and which is usually of sufficient size to carry 100 cards, is a pair of depending arms or brackets 31 and 32, one at each end thereof, carrying a shaft 33 on which is mounted a pair of star wheels 34 and 35 and a suitable knurled wheel 36 for turning the star wheels, these wheels being located in proper position so that the foremost card will fall from the chute into position between a pair of prongs of the stars and into position to be viewed, the remaining cards being held by a suitable spring arm 37 against falling forward when one of the cards is in position between the prongs of the star wheels. After the card has been viewed the turning of the star wheels will throw the lower end of the card rearwardly and the upper end thereof outwardly, so that the card will be carried out of the way and on to the lower chute, from which it will slide through the rear of the cabinet into the receptacle hereinbefore referred to. The spring arm 37 is provided 40 with a depending portion 38 which prevents the upper end of each card from falling too far forward, so that the star wheels will properly carry the lower edge of the card into position to be received by the chute. 45 The cards are maintained in their upright position on the upper chute by a suitable follower 39.

50 The upper chute forming the top of the cabinet is provided with a suitable handle 40, which when the cards are in position is out of the way, but when the cabinet is closed may be shifted into position to permit the use of the handle for carrying the cabinet. When the apparatus is not in use the stereoscope may be readily removed, as may

also the cards from the upper chute and stored away within the cabinet. When it is desired to use the same the stereoscope is removed and placed in the position shown in Fig. 1, the cards placed on the upper chute, the same having been swung into proper angular position and the lower door opened and adjusted into proper position for the reception of the reading matter.

55 The apparatus herein shown thus provides a very practical and comparatively inexpensive apparatus for not only storing the cards and the other parts necessary for use in such a device, but also furnishes a ready and convenient means for manipulating the cards without manually lifting and placing in position the successive cards, which is more or less a laborious procedure, while it also provides an efficient means for holding the stereoscope steadily so that the hands of 80 the operator may be used for turning the star wheel and the leaves of the manuscript or book placed upon the reading desk.

90 In operation, as the star wheels are rotated to shift a card away from the stereoscope the next succeeding card will be pushed forward so as to fall between the next succeeding pair of prongs of the star wheels in a manner which will be readily understood from the foregoing description. 95

I claim as my invention:

1. A stereoscopic apparatus comprising a cabinet having a chute for the reception of cards to be viewed, and means for receiving the cards from the chute and for 100 positioning them to be viewed.

2. A stereoscopic apparatus comprising a cabinet having a part thereof shiftable to form a wall of the cabinet or to form a card holding chute, and means for receiving the cards from the chute and for positioning 105 them to be viewed.

3. A stereoscopic apparatus comprising a cabinet having a part thereof shiftable to form a wall of the cabinet or to form a card holding chute, and means for receiving the cards from the chute and for positioning 110 them to be viewed and successively directing the cards away from the chute.

4. A stereoscopic apparatus comprising a 115 cabinet having a shiftable chute for the reception of cards to be viewed, and means for receiving the cards from the chute and for positioning them to be viewed.

5. A stereoscopic apparatus comprising a 120 cabinet having the top thereof shiftable to form a card holding chute, and means for receiving the cards successively from the chute and for directing them away therefrom.

6. A stereoscopic apparatus comprising a cabinet having the top thereof shiftable to form a card holding chute, and means for receiving the cards successively from the chute and for directing them away there- 130

- from and comprising star wheels and means for rotating them.
7. A stereoscopic apparatus comprising a cabinet having a part thereof shiftable to 5 form a wall of the cabinet or to form a card holding chute, means for receiving the cards from the chute and for successively directing them away from the chute, and means for receiving the cards therefrom.
- 10 8. A stereoscopic apparatus comprising a cabinet having a part thereof shiftable to form a wall of the cabinet or to form a card holding chute, means for receiving the cards from the chute and for successively 15 directing them away from the chute, and means for receiving the cards therefrom and connected with the chute for shiftable movement into position simultaneously therewith.
- 20 9. A stereoscopic apparatus comprising a cabinet having a part thereof shiftable to form a wall of the cabinet or to form a card holding chute, means for receiving the cards from the chute and for successively directing 25 them away from the chute, and means for receiving the cards therefrom and connected with the chute for shiftable movement into position simultaneously therewith and comprising a partition adapted to 30 divide the cabinet into a pair of compartments.
10. A stereoscopic apparatus comprising a cabinet having a chute for the reception of cards, means for receiving the cards from the chute and for successively directing them away therefrom, and means for conveying the cards away from the chute.
- 35 11. A stereoscopic apparatus comprising a cabinet having a chute for the reception 40 of cards, means for receiving the cards from the chute and for successively directing them away therefrom, and means for conveying the cards away from the chute and comprising a shiftable partition adapt-45 ed in one position to divide the cabinet into a pair of compartments and in another position to constitute the card conveying means.
- 50 12. A stereoscopic apparatus comprising a cabinet having the top thereof shiftable to 55 form a card holding chute, means for receiving the cards successively from the chute and manually operative for directing them away therefrom, and a shiftable partition adapted to divide the cabinet into a pair of compartments and connected with the chute for movement therewith into position to convey the cards away from the chute.
- 60 13. A stereoscopic apparatus comprising a cabinet having the top thereof shiftable to 65 form a card holding chute, means for receiving the cards successively from the chute and manually operative for directing them away therefrom, a shiftable partition
- adapted to divide the cabinet into a pair of compartments and connected with the chute for movement therewith into position to convey the cards away from the chute, and means for holding the cards on the chute. 70
14. A stereoscopic apparatus comprising a cabinet having the top thereof shiftable to form a card holding chute, means for receiving the cards successively from the chute and manually operative for directing them away therefrom, a shiftable partition adapted to divide the cabinet into a pair of compartments and connected with the chute for movement therewith into position to convey the cards away from the chute, and means for holding the cards on the chute and also constructed to limit the forward movement of each card as it is directed away from the chute. 75
15. A stereoscopic apparatus comprising a cabinet having a part thereof shiftable to form a wall of the cabinet or to form a card holding chute, and a part thereof forming a door and shiftable into position to 80 form a reading desk. 85
16. A stereoscopic apparatus comprising a cabinet having a part thereof shiftable to form a wall of the cabinet or to form a card holding chute and a part thereof forming a door and shiftable into position to 85 form a reading desk, and means for receiving the cards from the chute and manually operative to direct them away therefrom. 90
17. A stereoscopic apparatus comprising a cabinet having a part thereof shiftable to 95 form a wall of the cabinet or to form a card holding chute and a part thereof forming a door and shiftable into position to form a reading desk, means for receiving the cards from the chute and manually operative to direct them away therefrom, and means for conveying the cards away from the chute. 100
18. A stereoscopic apparatus comprising a cabinet having a part thereof shiftable to 105 form a wall of the cabinet or to form a card holding chute and a part thereof forming a door and shiftable into position to form a reading desk, means for receiving the cards from the chute and manually operative to direct them away therefrom, and means for conveying the cards away from the chute and comprising a shiftable partition adapt-110 ed in one position thereof to divide the cabinet into a pair of compartments.
19. A stereoscopic apparatus comprising a cabinet having a part thereof shiftable to 115 form a wall of the cabinet or to form a card holding chute and a part thereof forming a door and shiftable into position to form a reading desk, means for receiving the cards from the chute and manually operative to direct them away therefrom, and means for conveying the cards away from the chute and comprising a shiftable partition adapt-120 ed in one position thereof to 125

divide the cabinet into a pair of compartments and connected with the chute for movement therewith into its card conveying position.

- 5 20. A stereoscopic apparatus comprising a cabinet having a part thereof shiftable to form a wall of the cabinet or to form a card holding chute and a part thereof forming a door and shiftable into position to form 70
- 10 a reading desk, means for receiving the cards from the chute and manually operative to direct them away therefrom, means for conveying the cards away from the chute and comprising a shiftable partition adapted in 75
- 15 one position thereof to divide the cabinet into a pair of compartments and connected with the chute for movement therewith into its card conveying position, and an adjustable stereoscope carried by the cabinet. 80
- 20 21. A stereoscopic apparatus comprising a cabinet having a part thereof shiftable to form a wall of the cabinet or to form a card holding chute and a part thereof forming a door and shiftable into position to form 85
- 25 a reading desk, means for receiving the cards from the chute and manually operative to direct them away therefrom, means for conveying the cards away from the chute and comprising a shiftable partition adapted in 90
- 30 one position thereof to divide the cabinet into a pair of compartments and connected with the chute for movement therewith into its card conveying position, and an adjustable stereoscope carried by the cabinet and 95
- 35 having a shiftable nose-piece. 100
22. A stereoscopic apparatus comprising a cabinet having a part thereof shiftable to form a wall of the cabinet or to form a card holding chute and a part thereof forming 105
- 40 a door and shiftable into position to form a reading desk, means for receiving the cards from the chute and manually operative to direct them away therefrom, means for conveying the cards away from the chute and 110
- 45 comprising a shiftable partition adapted in one position thereof to divide the cabinet into a pair of compartments and connected with the chute for movement therewith into its card conveying position, and an adjustable and removable stereoscope carried by the cabinet. 115
- 50 23. A stereoscopic apparatus comprising a cabinet having the top thereof shiftable into an inclined position to form a card holding chute, and rotary means located adjacent to the outer end of the chute for receiving the cards successively from such chute and manually operative for directing them away therefrom. 120
- 55 24. A stereoscopic apparatus comprising a cabinet having the top thereof shiftable into an inclined position to form a card holding chute, rotary means located adjacent to the outer end of the chute for receiving the cards successively from such chute and manually operative for directing them away therefrom, an adjustable and removable stereoscope carried by the cabinet and 125
- 60 65 the cards successively from such chute and 130

manually operative for directing them away therefrom, and an adjustable and removable stereoscope carried by the cabinet.

25. A stereoscopic apparatus comprising a cabinet having the top thereof shiftable into an inclined position to form a card holding chute, rotary means located adjacent to the outer end of the chute for receiving the cards successively from such chute and manually operative for directing them away therefrom, and an adjustable and removable stereoscope carried by the cabinet and having a swinging nose-piece. 75

26. A stereoscopic apparatus comprising a cabinet having a top thereof shiftable into an inclined position to form a card holding chute, rotary means located adjacent to the outer end of the chute for receiving the cards successively from such chute and manually operative for directing them away therefrom, an adjustable and removable stereoscope carried by the cabinet and having a swinging nose-piece, and means for conveying the cards away from said chute. 85

27. A stereoscopic apparatus comprising a cabinet having the top thereof shiftable into an inclined position to form a card holding chute, rotary means located adjacent to the outer end of the chute for receiving the cards successively from such chute and manually operative for directing them away therefrom, an adjustable and removable stereoscope carried by the cabinet and having a swinging nose-piece, and means for conveying the cards away from said chute and comprising a shiftable partition adapted to divide the cabinet into a pair of compartments. 95

28. A stereoscopic apparatus comprising a cabinet having the top thereof shiftable into an inclined position to form a card holding chute, rotary means located adjacent to the outer end of the chute for receiving the cards successively from such chute and manually operative for directing them away therefrom, an adjustable and removable stereoscope carried by the cabinet and having a swinging nose-piece, and means for conveying the cards away from said chute and comprising a shiftable partition adapted to divide the cabinet into a pair of compartments and connected with said chute for movement into its card conveying position simultaneously with the shifting of such chute. 110

29. A stereoscopic apparatus comprising a cabinet having the top thereof shiftable into an inclined position to form a card holding chute, rotary means located adjacent to the outer end of the chute for receiving the cards successively from such chute and manually operative for directing them away therefrom, an adjustable and removable stereoscope carried by the cabinet and having a swinging nose-piece, and 115

- means for conveying the cards away from said chute and comprising a shiftable partition adapted to divide the cabinet into a pair of compartments and connected with 5 said chute for movement into its card conveying position simultaneously with the shifting of such chute, said cabinet having a door shiftable into position to form a reading desk below the stereoscope.
- 10 30. A stereoscopic apparatus comprising a cabinet having the top thereof shiftable into an inclined position to form a card holding chute, rotary means located adjacent to the outer end of the chute for receiving the cards successively from such chute and manually operative for directing them away therefrom, an adjustable and removable stereoscope carried by the cabinet and having a swinging nose-piece, and means 15 for conveying the cards away from said chute and comprising a shiftable partition adapted to divide the cabinet into a pair of compartments and connected with said chute for movement into its card conveying position simultaneously with the shifting 25 of such chute, said cabinet having a door shiftable into position to form a reading desk below the stereoscope and also a part of one of its walls shiftable and connected with said partition whereby on the shifting 30 of said partition into position to convey the cards away from the chute said part will be shiftable to open the cabinet to permit the cards to pass therefrom.
- Signed at 1821 Park Row Building, New York, N. Y., this 27th day of April, 1911.
